AUTOMATIC TIME CONTROL DEVICE
FOR COIN-OPERATED PHONOGRAPH
APPARATUSLyndon A. Durant, Chicago, Ill., assignor to
Royal Patent Corporation

Application May 21, 1947, Serial No. 749,486

2 Claims. (Cl. 161—1)

1

This invention relates to an automatic time control device for coin-operated phonograph apparatuses in which the timing device comprises an arrangement for periodically conditioning the phonograph apparatus for play without the employment of a coin.

The object of the invention is to provide a device of this character which by the playing of the phonograph through the automatic control of the timing device, will create a desire upon the part of those listening to the playing of the phonograph, to continue the operation of the phonograph apparatus by the use of coins.

Another object of the present invention resides in the provision of means for releasing a movable switch actuating member to a normal or initial position at any time from the start of its movement to the completion thereof as and when the phonograph motor circuit is continued for operation by the use of a coin.

Another object of the invention is the provision of an arrangement whereby the length of the non-playing interval of the phonograph apparatus may be varied when the phonograph is not conditioned for operation by a coin.

Another object of the invention is the provision of a control device of the character hereinafter set forth which comprises relatively few parts, with the result that the device may be expeditiously manufactured at an economical cost.

This invention constitutes an improvement over that disclosed in my Patent No. 2,421,835, granted June 10, 1947, on a Time-controlled mechanism for phonograph apparatuses.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a container within which the device is confined;

Fig. 2 is a sectional detail view taken substantially on line 2—2 of Fig. 1;

Fig. 3 is a perspective view of a spiral track embodied in the invention;

Fig. 4 is a perspective view of the device removed from within its enclosure;

Fig. 5 is a perspective view of the device shown in Fig. 1, taken from the left-hand side thereof;

Fig. 6 is a top plan view of the device illustrated in Fig. 4.

The several objects of my invention are accom-

2

plished by the preferred form of construction shown in the accompanying drawings, in which the enclosure is indicated at 10 and comprises a bottom section 11 and a removable cover 12.

To a wall 13 of this enclosure is secured as at 5 14 a mounting bracket 15. Carried by this mounting bracket 15 to one side of the medial portion 16 thereof is a motor 17 connected by suitable wire clips 18 to a suitable source of electric energy.

10 This motor includes an armature shaft 19, and secured to this shaft 19 as at 20 is a spool 21 providing a spiral track 22 terminating at one end into a cam 23.

15 Extending from the medial portion of the bracket 15 is a stationary stud 24. This stud 24 has mounted thereon an oscillatory carriage plate 25. Pivotedly connected to the carriage plate by means of a pintle screw 26 is a track arm 27 normally pivoted to the inner end 28 of the spiral track 22 by means of a spring 29 having a coil portion 30 coiled about the pintle screw 26 and having one end 31 connected to the track arm 27 and the opposite end 32 connected to the pintle screw 26 by insertion in a slot 33 formed in the head of this screw 26. The plate 25 is oscillated against the action of a spring 34 coiled about the stud 24, with one end portion of the spring 34 connected as at 35 to the stud 24 and the opposite end portion 36 connected to the carriage plate 25.

20 The carriage plate 25 is maintained in its position upon the stud 24 by means of a cotter pin 37. Secured by spot welding or the like to the carriage plate 25 is the upstanding portion 38 of a reset arm 39, the end 40 of which has a magnetically attractive plate 41 attached thereto, and disposed beneath the core of an electromagnetic coil 42. This coil 42 is connected in circuit with the phonograph motor circuit (not shown) through the medium of wire eyelets 43. The coil 42 is insulated from a supporting arm 44, and this arm 44 is connected as at 45 to the medial portion 16 of the bracket 15.

25 Carried by the mounting bracket 15 is a plate 46 on which is mounted and insulated therefrom the base 47 of a leaf spring switch 48, the base 47 being connected to the plate 46 by means of screws 49. The leaf springs 50 of this switch 50 are connected by means of connectors 51 to the phonograph starting circuit.

30 The track arm 27 includes a mounting boss 52, and adjustably projected through this boss 52 is a track pin 53 adapted to engage the spirals of 55 the track 22. The lower end portion of the arm

27 provides a lateral foot 54 which, under certain conditions, is adapted to engage the switch 48 and bear the spring leaves 50 thereof into contact with respect to each other.

In the cover 12 is formed an elongated slot 55. Movable in this slot is a guide plate 56 having upturned ends 57 serving as stops for engagement with the opposite end portions of the slot 55.

Beneath the cover 12 and carrying the guide plate 56, is an elongated plate 58 disposed for movement parallel with the adjacent surface of the cover 12 upon movement of the guide plate within the slot 55. Threaded into this plate 58 is a draw screw 59, the head 60 of which bears against the top surface of the wall 12 whereby when the screw is tightened the plate 58 will be drawn tightly against the adjacent surface of the cover 12 to hold the plate 58 in an adjusted position with respect to the cover 12. This plate 58 carries a depending finger 61 which is extended into the path of movement of the track arm 27.

A suitable switch (not shown) may control the source of power to the motor 17.

When the motor 17 is energized and the shaft 19 thereof rotated, the spool 21 will rotate in a clockwise direction as viewed in Fig. 4. The track pin 53 being disposed in the spiral track 22, will work longitudinally of the spool in a direction to pivot the track arm 27 in a clockwise direction as viewed in Fig. 4. When the track pin 53 reaches the end of the spiral track 22 (which is to the right as viewed in Fig. 4), the track pin will engage the inclined surface 23' of the cam 23 and, as the pin rides off this inclined surface 23', the foot 54 (which has an insulating jacket 54' thereon) will bear against the switch 48 and press the spring leaves thereof into contact with respect to each other, whereby to close a circuit to the phonograph starting circuit, whereupon the phonograph motor circuit will become energized and effect operation of the phonograph. The phonograph circuit has not been shown or described, as it constitutes no part of the present invention and may be any one of a number of standard phonograph circuits now commercially in use in connection with the operation of coin-controlled phonographs.

Upon energization of the phonograph motor circuit by action of the switch 48, the coil 42 will become energized and attract the arm 39 so as to pivot the carriage plate 25 in an anticlockwise direction as viewed in Fig. 4, whereby to disengage the track pin 53 from the cam 23 to permit pivotal movement of the track arm 27 in an anti-clockwise direction as viewed in Fig. 4, to dispose the track pin 53 at the starting point of the spiral track 22.

By actual experimentation, I have found that it takes approximately thirty minutes for the track pin 53 to travel from the beginning of the spiral track 22 to a position whereby it drops off the cam 23. There may be times when it is desired that this interval of inoperativeness of the phonograph be limited. To accomplish this, the finger 61 may be adjusted by movement of the plate 58 relative to the spool 21 to such position as it is desirable to have the track pin 53 start engagement with the track 22. For example, if this finger 61 were adjusted to a position midway between the ends of the track 22, the period of inoperativeness of the phonograph would in such case be approximately fifteen minutes. As before stated, this period may be varied in the manner just described. Let it be assumed that the finger 61 is adjusted so as to permit the track

pin 53 to travel the full length of the track 22. Further assuming that the track pin has completed but approximately one-half of its movement at which time the phonograph starting circuit is conditioned by the employment of a coin in a manner well-known in the phonograph art—under such conditions, as soon as the phonograph motor circuit is energized by the phonograph starting circuit the coil 42 will become energized and rock the carriage plate 25 to disengage the track pin 53 from the spiral track 22 and to allow the return of the track pin 53 to starting position with respect to the spiral track 22, the return of the track pin 53 being accomplished by the exertion of the spring 29 upon the track arm 27.

By this arrangement, should at any time before the phonograph is conditioned for play by the closing of the switch 48, a coin be employed in the usual and well-known manner to condition the phonograph for play, the track arm 27 will likewise return to its initial starting position by the operation of the coil 42 upon the carriage plate 25. On the other hand, should the phonograph be not conditioned for play by the employment of a coin within the period of the half hour, then at the end of the half hour period the phonograph will be automatically conditioned for play by the closing of the switch 48, which switch is closed in the manner hereinbefore stated.

From the foregoing description, I have provided a device which is efficient for effecting automatic operation of the phonograph apparatus at predetermined periods in the event that within such period the phonograph is not conditioned for play by the employment of a coin. The automatic playing of the phonograph will have the effect of encouraging those listening to the playing of the phonograph, to continue its operation by the employment of coins. When it is considered that over a given period of time the standard coin-controlled phonograph can only be played a certain number of times, it will be obvious that if the phonograph remains inoperative any great length of time there will result a considerable loss in the income derived from the playing of the phonograph by the employment of coins. Consequently this income can be stabilized if those listening to the playing of the phonograph can be induced to play the same by the employment of coins. The inducement to play the phonograph by the employment of coins is to start the playing of the phonograph automatically at predetermined intervals with the expectation that those listening to the phonograph will, because of such stimulus, continue the operation of the phonograph by the use of coins.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patents is:

1. A control device for controlling the operation of a coin-controlled phonograph at predetermined intervals comprising a starting switch, a member for closing said switch, means for supporting said member for movement into switch

closing position, means for moving said member into switch closing position, means for releasing said member from said moving means at the end of the movement of said member in one direction for movement in a direction from said switch closing position, said releasing means including a rockable carriage carrying said member, and an electromagnetic element for rocking said carriage in a direction to release said member from said moving means.

2. A control device for controlling the operation of a coin-controlled phonograph at predetermined intervals comprising a starting switch, a member for closing said switch, means for supporting said member for movement into switch closing position, means for moving said member into switch closing position, means for releasing said member from said moving means at the end of the movement of said member in one direction for movement in a direction from said switch closing position, said releasing means including a

rockable carriage carrying said member, and an electromagnetic element for rocking said carriage in a direction to release said member from said moving means, said moving means comprising a rotatable member having a spiral track, means for rotating said rotatable member, and a tracking member carried by said switch closing member and engaging said spiral track.

LYNDON A. DURANT.
